UNITED STATES PATENT OFFICE.

WILLIAM J. KENT, OF BROOKLYN, NEW YORK, ASSIGNOR TO NEW YORK BELTING & PACKING COMPANY, A CORPORATION OF NEW YORK.

METHOD AND APPARATUS FOR ASSEMBLING AND ATTACHING TILING.

1,350,410.

Specification of Letters Patent. Patented Aug. 24, 1920.

Application filed December 24, 1918. Serial No. 268,197.

To all whom it may concern:

Be it known that I, WILLIAM J. KENT, a citizen of the United States of America, residing in the borough of Brooklyn, city and

5 State of New York, have invented certain new and useful Improvements in Methods and Apparatus for Assembling and Attaching Tiling, of which the following is a specification.

10 My invention relates to assembling and connecting tiling of rubber, fiber or similar material, to form sheets or mats, and the purpose is to afford a method that will lend itself readily to this result, and to provide 15 automatic machinery to carry out such improved method.

In times past, products made from tiling, such as described, have been produced largely by hand, involving a very slow, laborious and expensive process, which is entirely done away with by my invention. By the present method, I aim to make it possible to handle large numbers of rubber and other tiling expeditiously and entirely by 25 automatic mechanism, and further to effect a tight and secure joint between the meeting edges of the various tiles.

I accomplish this by feeding the tiles, preferably in series or groups, of four for 30 instance, transversely with respect to a support or table upon which the sheet body, to which the tiles are to be attached, is arranged, and after a sufficient number of tiles have been fed transversely of the support to complete a row, they are caused to move toward said sheet body, or longitudinally of the support, being forced tightly against the adjacent edge of the sheet body which is preferably held tightly during such 35 operation. The tiles may be previously supplied with cement or other attaching medium applied to their several edges, and as soon as the pressure has been sufficient to cause them to adhere to the sheet body, the 40 latter is moved lengthwise of the support with the tiles attached and now forming a part of the body. The sheet body is then in position to permit feeding in of another row of tiles, and the operations can be repeated until the sheet body is of any length 45 desired, after which it is ready to be attached to a suitable base or backing, vulcanized if desired, cut into suitable shapes and otherwise finished according to well-known methods of manufacturing floor cov-

erings or mats of this type. Such a method can be used in connection with tiling of square, triangular, hexagonal or other configuration.

The mechanism by which I prefer to carry out the invention comprises generally a support or table which receives the sheet body as it is finished and permits it to be fed thereon, and arranged above the support to coöperate with the sheet body are sheet retaining means which normally hold the sheet rigidly in one position and are intermittently operated to release it and permit its being fed along after a row of tiling has been attached. The tiles are arranged 60 in magazines, preferably with cement already applied to their edges, and at regular intervals an ejector forces out tiles from the different magazines and moves them into the path of a tile feeding means. The 65 latter preferably consists of a reciprocatory member which forces the tiles in a direction transversely of or across the support previously mentioned. After having pushed one series or group of tiles forwardly, the 70 tile feeding means is retracted in the rear of a second group of tiles which the supplying mechanism furnishes. After this, the feeding means again moves forwardly, 75 pushing the last group of tiles into engagement with the previous group, and moving them all a corresponding distance forwardly. This operation continues until sufficient tiles have been fed in to complete a 80 row corresponding to the width of the sheet 85 body along the attaching edge. Immediately following this, there comes into operation a sheet attaching and feeding mechanism 90 which includes a follower that engages the adjacent edges of the fed-in tiles and initially forces them against the adjacent edge of the sheet body, while the latter is retained, preferably fixed in position. The edges of the fresh tiles are thus secured to 95 the sheet body and to each other, and thereupon the sheet body is released and the follower is again moved lengthwise of the support to feed the sheet along into position where it can receive a second row of tiles. The follower is finally retracted to 100 its normal position and the parts are then ready for a repetition of the operation just described.

To these and other ends, the invention 105 consists in certain improvements and com-

100

105

110

binations of parts as will be hereinafter more fully described, the novel features being pointed out in the claims at the end of the specification.

5 In the drawings:

Figure 1 is a plan view of an apparatus which illustrates one practical adaptation of the invention, and shows a preferred form of mechanism for carrying out the 10 method described;

Fig. 2 is a side elevation of the mechanism appearing in Fig. 1;

Fig. 3 is a plan view enlarged, and partially in section, showing the tile feeding 15 means and the operating devices therefor;

Fig. 4 is a sectional view on line 4—4 of Fig. 3;

Fig. 5 is a sectional view on line 5—5 of Fig. 3, and showing the relative position 20 of the parts as a new supply of tiles is being fed in;

Fig. 6 is a sectional view taken substantially on line 6—6 of Fig. 1 and illustrating the relative positions of the parts after the 25 alining guide is withdrawn and the follower has completed its initial movement;

Fig. 7 is a similar view showing the position of the parts after the pressure members have been raised to release the sheet 30 and the follower has completed its final movement;

Fig. 8 is a similar view showing the next step in the operations following Fig. 7, the follower having been retracted and the 35 alining guide restored to normal position;

Fig. 9 is a sectional view taken generally on the line 9—9 of Fig. 1;

Fig. 10 is an end elevation of the apparatus; and

40 Fig. 11 is an enlarged sectional view in detail of one of the tile magazines.

I have illustrated one practical embodiment of the invention, by which the novel method described can be carried out, although other structures may readily be designed to accomplish the same general purpose. In the mechanism shown, A designates the support or table for the sheet body or mat, which is formed in successive 45 steps by the attachment of successive rows of tiling, after each of which the sheet body is fed lengthwise of the support. The tiles are preferably fed transversely on the support A, and diagonally with reference to the 50 sides of the completed sheet body.

In the form illustrated, it is intended to use square tiles, and to feed them in at an angle of approximately 45° with reference to the sides of the completed sheet body.

60 These, however, are minor details and are not essential to the invention, which is likewise applicable for use with triangular, hexagonal, or other contours of tiles, and the latter may be fed transversely of the 65 sheet body at various angles other than 45°.

The mechanism shown is in accord with what I have found to be good practice, and I will now describe the tile supplying mechanism and feeding means.

70 *Tile supplying mechanism and tile feeding means.*

The tiles, which may be of rubber or other fibrous substance, are positioned in the series of square magazines B, four of 75 such magazines being shown. The tiles are arranged in vertical stacks in the magazines and at regular intervals, a tile is ejected from each magazine, such tile being conveniently, although not necessarily the lowermost one, as in the present disclosure. To this end, I employ a tile supplying mechanism consisting of a reciprocating ejector or slide C (Figs. 1, 3 and 4), slideable upon the support A and constructed so 80 as to pass through openings provided at the bottoms of the magazines B. The ejector C is connected by a link D with an arm E which is rotatably mounted upon a post F. The arm E also carries a tail-piece G 85 which is slotted or cut away at H (see Fig. 3), for a purpose presently to appear.

After the tile supplying mechanism forces the tiles from the magazines aforementioned, the tile feeding means comes into 90 operation and pushes the tiles across the support A. This feeding means, as shown in the present embodiment of the invention, comprises a slide or plunger I which travels between guides J and K and is connected by 95 a link L with an arm M, the latter being rotatably mounted on the post F already described. N designates a driving lever which is fixedly mounted on the post F and carries a sliding pin O adapted to engage a 100 corresponding opening in the arm M and lock the latter for movement with the post F. The arm M can thus be released from operation quickly by removing the pin O. The driving lever N and the post F are operated by means of a reciprocating rack P which engages a toothed segment Q keyed 105 on the post F. The reciprocating rack P has pivoted thereto a connecting rod R, the opposite end of which is joined to a lever S 110 pivotally mounted upon a support T and carrying a roller U which engages a cam slot V in the continuously rotating cam W. The cam slot V is so formed as to effect eight reciprocations of the connecting rod 115 R and rack P, after which the rack is held in its outermost position by the dwell portion X, and this likewise serves to maintain the tile feeding means, or slide I, in its retracted position, as shown in Fig. 1.

120 During the normal operation of supplying and feeding the tiles, it is desirable that the slide C be operated, to eject the tiles from the magazines B, after the slide I is retracted. In order to accomplish this, the 125

arm M, which is movable over a bridge Y (see Figs. 3 and 4), carries a pivoted dog Z, and mounted upon the latter is a roller A'. The roller A' engages the adjacent 5 edge of the bridge Y, and when it reaches the cut-away portion B', it permits the dog Z to move inwardly under the impulse of its controlling spring, and to engage the recess H in the tail-piece G already described. Further backward movement of the arm M then carries with it the tail-piece G, causing the arm E to rotate about the axis F, and thereby to move the slide C 10 forwardly and eject a series of tiles into the path of the feeding slide I. On the return movement, the ejector C is first retracted to the position shown in Fig. 3, whereupon the dog Z is moved out of the notch H by means of roller A' riding out of the recess 15 or cut-away portion B', and the feeding slide I then moves forwardly, engaging the tiles C' which have previously been forced into the path of the slide I by ejector C, and pushes them ahead to the position shown in Fig. 3. This operation likewise forces 20 ahead all the tiles which are in the path of the slide I.

In the arrangement shown, I have provided for supplying the tiles in groups of 25 four each, although this number may be varied to suit different requirements and under some conditions, it may be desirable to supply the tiles individually. The present machine is designed to successively supply and feed forwardly eight groups of 30 four tiles each, giving a total width of thirty-two tiles which are pushed transversely of the support at an angle of approximately 45° to the sides of the sheet 35 body, as shown in Fig. 1, until the farthest-most tile has reached the opposite side of the sheet body. At such time, the tile supplying and feeding instrumentalities are stopped for a given period to permit of attaching the 40 fed-in tiles to the sheet body and feeding the latter along one step on the support.

According to the preferred method of 45 operation, the tiles are provided with cement applied to their several edges, before being positioned in the magazines B, and as they are fed from the magazines by the ejector C, there may be a tendency for them to stick to the ejector and be drawn back on the return stroke of the latter. To prevent this, 50 I provide each magazine, preferably, with a spring follower D' (see Fig. 11), supported at the front thereof and immediately overlying the corresponding tile C' after it has been moved from the magazine. The 55 pressure of the spring E' which controls the follower D' is such as to hold the tile with sufficient force to prevent its being drawn back into the magazine, and at the same time permit the slide I to readily feed the 60 tiles forwardly.

Tile guiding mechanism, and sheet attaching and feeding mechanism.

During the feeding of the tiles, as previously described, they are held in line by an 70 alining guide F' along one edge, which extends across the support or table, and when in normal position is slightly above the same (see Figs. 5 to 8, inclusive). On their opposite edges, the tiles are engaged by the 75 adjacent surfaces G' of a follower H', which constitutes the essential part of the sheet attaching and feeding mechanism. The follower H' is provided with an extension or flange I', which overlies the tiles and 80 prevents their buckling as they are fed loosely across the support. After an entire row of tiles has been fed into position for attachment to the sheet body, the alining guide F' is automatically lowered to a point 85 flush with or beneath the support A, and the follower H' is then moved laterally to force the tiling tightly against the sheet body and attach it thereto.

The operations just referred to are illustrated by Figs. 5 and 6, respectively, and during these steps, the sheet body—which I will designate as J'—is held rigidly against the table and prevented from movement. After the tiles C' have been forced tightly 90 against the sheet body J', as shown in Fig. 6, they are held in this position for a period sufficient to cause the cement to unite them tightly. Then the sheet body is released in a manner that will be described later, and 95 the follower H' again moves laterally to force the sheet body, which now includes the tiling C', along the table and out of the path of the alining guide F', which is then again elevated and the parts made ready 100 to receive a new supply of tiles.

To accomplish the purposes just described, the follower H' is of the form shown in Fig. 1, extending preferably across the support A in a generally diagonal direction, and 110 slides on a guide K'. The follower H' is governed in its movement by a block L' which is adjustably associated with the follower by means of screws M' on the latter. The screws M' can be adjusted in the lugs 115 N' and engage opposite sides of the block L'. The latter is connected with a roller which travels in a cam slot O' in a continuously rotating cam wheel P', as shown in Figs. 1 and 2. The cam slot O' is of such 120 formation as to cause the follower H' to have an intermittent lateral travel lengthwise of the support A, the first part of the movement being sufficient to move the fed-in tiles against the sheet body. The follower then comes to rest in this position for a sufficient period, after which it again travels forwardly to feed the sheet body beyond the alining guide, and the follower 125 is then retracted to its normal position. The 130

follower is held in its intermediate position by the dwell portion Q' of the cam, while the part R' serves to move the follower to its extreme outward limit, after which it is retracted to normal position.

The alining guide F' is mounted on spring-controlled plungers S' which are arranged in fixed sockets T' , the latter being supported in the brackets U' . The plungers S' are provided with openings V' which receive the extension bars W' . The latter are carried by the follower H' through the instrumentality of downwardly projecting posts X' and suitable securing collars and nuts, as shown in Fig. 8. The extension bars W' are cut away at their ends, as shown at Y' , and have cam portions Z' which co-operate with corresponding inclined portions A^2 on the plungers S' . In the normal position as shown in Figs. 5 and 8, the plungers S' are free to move upwardly into the cut-away portion Y' of the bars W' . This permits the alining guide to project above the support A . As the follower H' is moved laterally, the cam surfaces Z' engage the co-operating surfaces A^2 on the plungers and force the latter downwardly, as shown in Figs. 6 and 7, thereby holding the alining guide beneath the surface of the support during the operation of attaching the tiles to the sheet body and feeding them lengthwise of the table. It is not until the follower H' is retracted to its normal position, as shown in Fig. 8, that the alining guide is again permitted to assume its uppermost position, and the parts are then ready to receive another supply of loose tiling.

Sheet retaining means.

40 During the operation of attaching the fed-in tiles to the sheet body, it is preferred to hold the body rigidly in order that the necessary pressure can be exerted against it, and this may be accomplished by sheet retaining means, such as I have employed, and which includes gripping members that engage the side edges of the sheet and pressure members engaging the upper surface of the work end or attaching end of the sheet.

45 The pressure members referred to consist of spring plungers B^2 , preferably one being provided for each tile along the work edge of the sheet body. Each plunger B^2 has a base C^2 , which engages the surface of the sheet and is guided by a pin D^2 engaging an opening E^2 in the carrier F^2 on which the plungers are mounted. Each plunger is held in position by a threaded collar B^2 and arranged between the collar G^2 and a shoulder H^2 on the plunger, is a spring I^2 which tends to force the plunger downwardly, the latter being limited in its downward movement by the nut J^2 . By this arrangement, when the carrier F^2 is moved 60 downwardly toward the sheet body, the

pressure members C^2 engage the sheet yieldingly, but with sufficient force to hold it against the pressure of the follower H' , which would otherwise cause it to move lengthwise of the support A . When the carrier is moved to its lowermost position, the parts are arranged as shown in Figs. 5 and 6. The necessary intermittent movements of the carrier upwardly and downwardly are effected in the following manner.

The ends of the carrier are mounted on vertically movable posts K^2 (see Figs. 2 and 9), and these are pivotally connected to levers L^2 which are fixed on the rock shafts M^2 , the latter being supported in stationary brackets N^2 . The rock shafts M^2 also have fitted thereon inwardly extending levers O^2 which are connected at their adjacent ends and provided with a roller P^2 engaging a cam-way Q^2 in the continuously rotating cam-wheel R^2 . The cam-way Q^2 is so formed that the pressure members are held in their downward positions during the larger part of the rotation of the cam-wheel, and are elevated only for a short period, which is sufficiently long to permit the sheet body to be fed lengthwise of the table the width of one row of tiles, after the latter have been attached.

In addition to the pressure members just described, the sheet body is also held by gripping members consisting of bars S^2 which engage the side edges of the sheet and are serrated or angular to fit the corresponding corners of the tiles. The bars S^2 are slidable back and forth on the support A , as shown in Fig. 5. Each bar S^2 is provided with posts T^2 which project through slotted openings U^2 in the support A . The posts T^2 are movable back and forth in slots U^2 to advance and retract the locking bars S^2 toward and from the sides of the sheet body. To this end, the lower ends of the posts T^2 are connected to angle levers V^2 (see Fig. 1), which are pivoted on stationary bearings and connected by links W^2 with a block X^2 (see Fig. 2). The block X^2 carries a roller Y^2 which engages a cam slot Z^2 in the cam-wheel A^3 . The cam-wheel A^3 rotates continuously and the cam-slot Z^2 is so formed as to operate the block X^2 and links W^2 to withdraw the side bars S^2 simultaneously with the elevation of the pressure members already described.

The cam-wheels W , P' , R^2 and A^3 are all fixedly mounted on a common driving shaft B^3 which carries a worm-wheel C^3 . The latter is driven by a worm D^3 mounted on a shaft carrying a gear E^3 which is driven by a pinion I^3 on the motor shaft.

Operation.

The parts being in the positions shown in Figs. 1 and 5, the slide I moves inwardly, feeding the tiles in front of it, and is then

retracted, after which the ejector C forces another series of tiles from the magazines. This alternate operation of the ejector and feeding slide continues until the loose tiles 5 extend entirely across the width of the sheet body, assuming the position shown in Fig. 5. When the row of tiles is completed, the operation of the supplying and feeding devices stops, the alining guide is actuated 10 downwardly, and the follower H' is moved to force the tiles against the sheet body, as shown in Fig. 6. This presses the tiles together and secures them tightly by the cement which has already been applied to 15 the edges. Immediately thereafter, the pressure members C² are elevated, and the gripping members S² are withdrawn laterally, freeing the sheet body, and the follower H' again moves laterally still farther 20 forcing the sheet body to the position shown in Fig. 7. The follower H' is then retracted to its normal position, the members S² returned, and the alining guide F' elevated to its normal position and the parts 25 are ready for a repetition of the operation.

It will be understood that the mechanism shown and described constitutes only one embodiment of my invention, being that one adapted to assemble square tiles in oblique 30 order. The invention is subject to modification or rearrangement according to the particular use required, varying with the shape of the tiles, the number in each group, the angle of feeding, and other conditions, 35 all as will be understood by mechanics or engineers.

After the tiles have been assembled in sheet form they may be attached in any suitable manner to a base or backing and otherwise 40 finished according to well-known methods of manufacture.

What I claim is:—

1. A method of assembling and attaching tiling to form sheets or mats, consisting in 45 feeding tiles having adhesive sides edgewise and transversely with respect to a sheet body until a row of required length is completed, forcing said tiles edgewise against the adjacent edge of the sheet to secure them thereto, 50 and feeding the sheet longitudinally to make room for another row of tiles.

2. A method according to claim 1, characterized in that the tiles are fed transversely of the sheet body in successive series or 55 groups positioned end to end.

3. A method according to claim 1, characterized in that the tiles are fed transversely of the sheet body on a diagonal line with 60 reference to the side edges of the sheet body.

4. A method according to claim 1, characterized in that the tiles are fed transversely of the sheet body at an angle of approximately forty-five degrees to the side edges of the sheet body.

5. Mechanism for assembling and attach-

ing tiling to form sheets or mats consisting of a sheet support, tile feeding means operating to feed tiles transversely of the support, and tile attaching and sheet feeding mechanism acting to force the tiles against a sheet 70 body and to feed the sheet lengthwise of the support.

6. Mechanism according to claim 5, characterized further by sheet retaining means which holds the sheet body while the tiles 75 are forced against and secured to it and thereafter automatically releases the sheet.

7. Mechanism according to claim 5, in which the tile attaching and sheet feeding mechanism imparts an intermittent movement to the tiles, to first force and hold them against the sheet body and thereafter move 80 the sheet longitudinally of the support.

8. Mechanism according to claim 5, characterized further by tile supplying mecha- 85 nism which intermittently positions a plurality of tiles in the path of the tile feeding means.

9. Mechanism according to claim 5, characterized further by tile supplying mecha- 90 nism comprising a series of vertical tile magazines, and an ejector which intermittently engages tiles in the magazines and moves them into the path of said tile feeding means. 95

10. Mechanism according to claim 5, in which the tile feeding means comprises a reciprocatory member, and characterized further by tile supplying mechanism comprising a series of vertical tile magazines, 100 and a reciprocatory ejector which intermittently engages tiles in the magazines and moves them into the path of said reciprocatory member, the latter moving at right angles to said ejector and alternately toward 105 and from a common point.

11. Mechanism according to claim 5, in which the tile feeding means comprises a reciprocatory member, and characterized further by tile supplying mechanism comprising a series of vertical tile magazines, 110 and a reciprocatory ejector which intermittently engages tiles in the magazines and moves them into the path of said reciprocatory member, the latter moving at right angles to said ejector and alternately toward 115 and from a common point, and operating instrumentalities which initially retract said reciprocatory member and thereafter move the ejector forwardly to supply a series of tiles into position to be engaged when the reciprocatory member again moves forwardly.

12. Mechanism according to claim 5, in which the tile attaching and sheet feeding 125 mechanism comprises a follower extending across the support parallel to the adjacent edges of the fed-in tiles, and operating instrumentalities acting to advance the follower lengthwise of the support. 130

13. Mechanism according to claim 5, in which the tile attaching and sheet feeding mechanism comprises a follower extending across the support parallel to the adjacent edges of the fed-in tiles, the follower having a projecting flange coextensive lengthwise therewith and adapted to overlie the row of fed-in tiles, and operating instrumentalities acting to advance the follower lengthwise of the support.

14. Mechanism according to claim 5, in which the tile attaching and sheet feeding mechanism comprises a follower extending across the support parallel to the adjacent edges of the fed-in tiles, the follower having a projecting flange coextensive lengthwise therewith and adapted to overlie the row of fed-in tiles, and operating instrumentalities acting to first advance the follower so as to force and hold the fed-in tiles against the sheet body, and thereafter move the entire sheet lengthwise of the support.

15. Mechanism according to claim 5, in which the tile attaching and sheet feeding mechanism comprises a follower extending across the support parallel to the adjacent edges of the fed-in tiles, and operating instrumentalities acting to first advance the follower so as to force and hold the fed-in tiles against the sheet body, and thereafter move the entire sheet lengthwise of the support.

16. Mechanism according to claim 5, characterized further by sheet retaining means, consisting of gripping members engaging the side edges of the sheet and pressure members engaging the upper surface of the work end of the sheet, and operating instrumentalities acting automatically to intermittently elevate said pressure members and withdraw said gripping members to release the sheet.

17. Mechanism according to claim 5, characterized further by an alining guide against which the tiles are fed, and devices acting to withdraw said guide from the path of the tiles previously to the operation of said sheet attaching and feeding mechanism.

18. Mechanism according to claim 5, characterized further by tile supplying mechanism which positions tiles in the path of the tile feeding means.

19. Mechanism according to claim 5, in which the tile attaching and sheet feeding mechanism comprises a follower extending across the support parallel to the adjacent edges of the fed-in tiles, and operating instrumentalities operating to advance the follower lengthwise of the support.

20. Mechanism according to claim 5, characterized further by sheet retaining means including pressure members engaging the upper surface of the end of the sheet, and operating instrumentalities acting au-

tomatically to intermittently elevate said pressure members and release the sheet.

21. A machine for assembling tiling including in combination means for supplying tiles, means for moving the tiles bodily side- 70 wise to form a unit of the required length, and means for shifting the resulting unit of tiles in a direction transverse the direction of the bodily sidewise movement whereby the tiles may be assembled in sheet form. 75

22. A machine for assembling tiles including in combination means for supplying tiles, means for moving the tiles edgewise to form a unit of a required length, means for guiding the tiles during their edgewise 80 movement, and means for shifting the units of tiles in a direction transverse the direction of their edgewise movement.

23. A machine for assembling tiles including in combination means for supplying tiles, means for moving the tiles edgewise to form a unit of a required length, and means for shifting a unit of tiles in a direction transverse the direction of their edgewise movement, and means for preventing buck- 90 ling of the tiles in a unit.

24. A machine for assembling tiles including in combination means for supplying tiles, means for moving the tiles edgewise to form a unit of the required length, means for shifting each unit of tiles in a two stage movement in a direction transverse the direction of their edgewise movement, and means for temporarily holding the sheet during the first stage of each unit's movement in 100 order to squeeze the preformed sheet and the unit together.

25. A machine for assembling tiles including in combination means for supplying tiles, means for moving the tiles edgewise to 1 form a unit of the required length, means for shifting each unit of tiles in a two stage movement in a direction transverse the direction of their edgewise movement, and means for temporarily holding the sheet 110 during the first stage of each unit's movement in order to squeeze the preformed sheet and the unit together, said last named means including devices for applying pressure to the sides and faces of the preformed sheet. 115

26. A method of assembling and attaching tiling to form sheets, consisting in applying adhesive to the sides of tiles, feeding the tiles edgewise and transversely with respect to a sheet body until a row of the required 120 length is applied, forcing said row of tiles edgewise against the adjacent edge of the sheet in order to secure it thereto, and feeding the resulting sheet longitudinally to make room for another row of tiles.

27. A method of assembling polygonal tiling consisting in feeding tiles successively to form rows of a desired length, shifting each row of tiles after its formation in a direction at an angle to a side of the individual po- 130

lygonal tiles, and subsequently attaching a backing to a sheet of the thus assembled tiles.

28. A method of assembling polygonal tiling, consisting in feeding groups of tiles successively to form units of the desired length, shifting each unit of the tiles after its formation in a direction at an angle to a side of the individual polygonal tiles, and subsequently attaching a backing to the resulting sheet.

29. A method of assembling polygonal tiling consisting in applying adhesive to the edges of the tiles, feeding tiles successively to form rows of a desired length, shifting each row of tiles after its formation in a

direction at an angle to a side of the individual polygonal tiles, and subsequently attaching a backing to a sheet of the thus assembled tiles.

30. A method of assembling polygonal tiling consisting in applying adhesive to the edges of the tiles, feeding groups of tiles successively to form units of the desired length, shifting each unit of tiles after its formation in a direction at an angle to a side of the individual polygonal tiles, and subsequently attaching a backing to the resulting sheet.

In witness whereof, I have hereunto signed my name.

WILLIAM J. KENT.
